W. CRAMER

BELT LACING DEVICE

Filed Oct. 30, 1924

FIG. I

FIG. II

FIG. III

UNITED STATES PATENT OFFICE.

WILLIAM CRAMER, OF ST. LOUIS, MISSOURI, ASSIGNOR, BY MESNE ASSIGNMENTS, TO
ISIDOR M. JACOBS.

BELT-LACING DEVICE.

Application filed October 30, 1924. Serial No. 746,763.

This invention relates to improvements in belt lacing devices of the type used to apply metallic belt lacings to power transmission belts for the purpose of securing the ends of said belts together, and particularly to a device of the type mentioned which is provided with a cutting device for trimming the end portions of the belts to be acted on, and a pivot hammer for driving the metallic lacing members through the belts and clinching said lacing members.

A belt fastening device of the type mentioned above is provided with a pivot blade having an inclined face which is the result of tapering said blade to produce a cutting edge. This inclined face, prior to this invention, had the effect of causing the blade to be moved laterally as it was forced through the belt which was being severed whereby an irregular cut was produced. To eliminate any lateral movement of the blade forming a part of my improved belt lacing device, I employ a guide member which may be arranged immediately adjacent to said blade as it is forced through the belt, thus causing said blade to move in a true vertical line.

Another advantage of my improved belt lacing device over the belt lacing devices heretofore used resides in the fact that the pivoted hammer of said belt lacing device comprises a plurality of hammer members instead of a single hammer member. By so arranging the pivot hammer of my device the necessity for a tremendously heavy blow to drive through the belt and clinch a great number of lacing members is eliminated, as only a portion of the total number of lacing members are driven through the belt and clinched by each blow and the blows therefore need not be so heavy as if all of said lacing members were clinched by each blow.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications

which come within the scope of the claims hereunto appended.

Fig. I is a plan view of a belt lacing device made in accordance with my invention.

Fig. II is a longitudinal section through the device shown in Fig. I.

Fig. III is a transverse section through the device shown in Figs. I and II.

In the drawing A designates my improved belt lacing device which comprises an anvil B and staple holding mechanism C. The anvil B is preferably formed of comparatively heavy metal and is provided with a plurality of reinforcing ribs B' which are intended to add durability to said anvil. Mounted on the anvil B adjacent to one of its ends is the staple holding mechanism C, said mechanism comprising a plate 1 which is secured to the anvil B, preferably by means of rivets 2. The plate 1, as shown in Fig. I of the drawing, extends approximately the full width of the anvil B, and said plate is provided with a plurality of slots 3 formed along its front edge. Formed through each of the tooth-like portions 4 of the plate 1 is an aperture, and the apertures in the various tooth-like portions 4 are in alignment with each other so that a continuous passageway is formed which extends from end to end of the slotted portion of said plate 1. Extended through the apertures referred to is an elongated pin 5, said pin being preferably provided with a loop at one of its ends to provide a convenient means for withdrawing said pin from said apertures.

Arranged adjacent to the plate 1 of the staple holding mechanism of my improved device is a hammer D which comprises a pair of independently movable hammer members 6 and 7, said members 6 and 7 being pivotally mounted on a rod 8 which extends transversely of the anvil B. The hammer members 6 and 7 each comprise a hub portion 9, a head portion 10 and a curved arm 11 connecting the associated hub portion and head portion. 12 designated stop members which are formed integral with the hub portions of the hammer members 6 and 7, said stop members being so arranged that they will contact with the under side of the top wall of the anvil B when said members

6 and 7 have been moved rearwardly, as shown by dotted lines in Fig. II. It is, of course, plain that the purpose of the stop member 12 is to limit the rearward movement of the hammer members 6 and 7. The hammer members 6 and 7 are arranged immediately adjacent to each other in a horizontal direction, the inner ends of the head portions 10 of said hammer members being almost in contact with each other (Fig. I). 10 13 designates a coil spring, the opposite ends of which are attached to the members 6 and 7 to connect said members together.

Located adjacent to a side edge of the anvil B is the cutting device of my improved belt lacing device, which comprises a blade 14 which is pivotally mounted on the transverse rod 8 by which the hammer members 6 and 7 are supported. The blade 14 is 15 provided with an inclined face 15 which results from tapering said blade to provide it with a cutting edge. 16 designates an L-shaped member which is secured to the side of the anvil B to provide a recess into 20 which the blade 14 is moved when it is passed through a belt, said recess being approximately as wide as the thickness of the blade and the inner wall of said recess functioning as a cutting edge which cooperates with the blade to sever the belt. Supported in bearings 17 formed integral with the rear wall 18 of the anvil B is a transverse rod 19, said rod being rotatably supported in said bearings. Fixed to the rod 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

upper edge of the wall 18 of the anvil, as shown in Fig. II.

In the use of my improved belt lacing device it is first necessary to trim the opposite end portions of the belt so that the 70 meeting edges thereof will be provided with faces which are cut at right angles to the top and bottom faces and the side edges of said belt. The belt to be trimmed is placed laterally of the anvil B so that the portion 75 to be cut from said belt extends beyond the cutting edge of the blade 14 and so that a side edge of said belt contacts with the inside face of the end wall 18 of the anvil B. When the belt is positioned as described, 80 the blade 14 is struck a hammer blow and said blade is driven through the belt to sever same. It will be remembered that the blade 14 is provided with an inclined face 15, and if some means were not present to prevent it, this inclined face acting against the belt through which it is being forced would have a tendency to move said blade inwardly and thereby produce an irregular cut. However, the curved arm 20 85 of my improved device will have been previously raised to its upright position and will be so located relative to the blade 14 that said blade will rub against it as it moves downwardly under the force of the hammer blow. It is therefore plain that lateral movement of the blade 14 will be prevented, and as said blade moves in a true vertical line a square cut will be obtained.

After the belt has been trimmed as described, the elongated pin 5 is withdrawn from the apertures through which it extends and a staple is inserted into each of the slots of the plate 1, or into as many 105 slots as is necessary, depending on the width of the belt to be acted upon. The elongated pin is then again inserted into the apertures in a manner to lock said staples in said slots. An end of the belt is then inserted between the sharp ends of the staples and the hammer members 6 and 7 are brought to positions where they rest upon said staples. After the parts have been thus positioned, one of the hammer members 6 or 7 will be struck a hammer blow which will drive the sharpened ends of the staples located below said member into the belt and clinch same. The other hammer member will then be struck a blow which will drive the sharpened ends of the staples below that member into the belt and clinch said ends of said staples. It is plain from this that because a fewer number of staples are driven through the belt and clinched by each blow, a much lighter blow will be sufficient than if all of the staples were driven through the belt and clinched by a single blow. After both ends of the belt have been provided with staples in the manner described, the 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

staples at the opposite ends of said belt are connected together in the well known manner.

I claim:

- 5 1. A belt lacing device comprising an anvil, staple holding mechanism, and a pivoted hammer, said hammer comprising a plurality of independently movable hammer members.
- 10 2. A belt lacing device comprising an anvil, staple holding mechanism, and a pivoted hammer, said hammer comprising a plurality of independently movable hammer members, and flexible means whereby said hammer members are connected together.
- 15 3. A belt lacing device comprising an

anvil, staple holding mechanism, and a pivoted hammer, said hammer comprising a pair of independently movable hammer members, and a coil spring whereby said 20 hammer members are connected together.

4. A belt lacing device comprising an anvil, staple holding mechanism, and a pivoted hammer, said hammer comprising a pair of independently movable hammer 25 members, a coil spring whereby said hammer members are connected together, and stop members for limiting the rearward movement of said hammer members.

In testimony that I claim the foregoing 30 I hereunto affix my signature.

WILLIAM CRAMER.
